NECKTIE ENGAGING COLLAR

Joseph P. Wilson, Columbia, S. C.

Application August 2, 1940, Serial No. 349,499

4 Claims. (Cl. 2—137)

This invention relates to wearing apparel, particularly collars, either attached to or detachable from a shirt and has as its principal object the provision of novel means contained on a collar or the like whereby a commercial necktie operable with said collar may be elevated to and desirably positioned at the top of the neckband junction or crotch on said collar by the usual manual movement of said necktie on said collar during the usual operation preceding and ending with positioning of the knot adjacent or against the front collar holding button while said collar and necktie are customarily positioned on the wearer's neck portion. Said novel means provides, incidentally, a desirable reinforcement of said collar at needed points. Other objects, novel aspects and desirable gains of the invention are encompassed in the various details of construction, arrangement and procedure of operation of the members of the illustrative embodiment set forth in detail herein, all of which will become apparent as the description proceeds in the light of the annexed drawing, in which:

Fig. 1 illustrates a collar attached to a shirt, the flap of said collar having been raised vertically from its normal position so that the necktie elevating, positioning and collar reinforcement means may be clearly seen.

Fig. 2 illustrates a necktie with the center portion of the longitudinal structure broken away, the opposing ends of said necktie being shown along with the seam, which in commercial neckties extends longitudinally from end to end in the rear center of its elevation.

Fig. 3 illustrates a normal collar and necktie assembly, a four-in-hand necktie being nominally knotted and made ready to be drawn into normal wearing position against the collar.

General statement of construction and operation.—Referring to Fig. 1: Protuberant members 5, 6, 7, 8, 9 and 10 are positioned on the outer surface of the neckband structure 1 in a manner divergent to the elevational and longitudinal degrees of said structure with said members diverging upwardly from the bottom portion 1A of said structure and with said members starting their upward divergence from the (left hand end) buttonhole portion and commencing with the member 5 and continuing in spaced sequence along the longitudinal structure to and including the member 10 positioned oppositely at the (right hand end) button portion of said structure, there being a greater plurality of said members at said button end portion, viz. mem-

bers 7, 8, 9 and 10, than that contained on said buttonhole end portion, viz. members 5 and 6. Said button end portion members 5 and 6 being of shorter length and more inclined to the vertical in their said divergence than are the said members contained on the said buttonhole end portion of said structure, thus, when a necktie, drawn from left to right normally, is introduced into engagement with said members, and, starting with initial member 5, said moving necktie is induced into a starting rise toward the crotch 12, said rising movement being accelerated and completed by later engagement with the sharper inclined members on the button end portion of said structure.

A member 11 is positioned substantially in the center of the longitudinal and elevational degrees of the collar flap 4, said member 11 being divergent to both said degrees, with said divergence starting near the flap bottom portion 4C and extending upwardly to near the crotch 12, thus, when said flap 4 is in normal position for use the said flap member 11 is positioned as indicated in outline on the neckband 1 in Fig. 1, thus, when said necktie body 14 is engaged on its front surface by said member 11, said necktie body 14 being drawn along the said neckband 1, extra engaging pressure is imposed on the adjoining neckband members 6 and 7 by the necktie shoulder 17 and the necktie rear body, resulting in desired extra necktie elevating at said point, as it will be noted in Fig. 3 that the crotch 12 portion located at the longitudinal center of the collar construction is higher at said point than the crotch 12 portions located at either end adjacent the buttonhole 2 and button 3. Said protuberant members 5 to 11 in this embodiment are raised sewing machine formed stitches sewn through the neckband 1 and flap 4 fabrics. Said stitches are protuberant as shown for necktie engagement on the desired side of said fabrics and the said stitches lay flat, desirably, on the reverse side of said fabrics.

Detailed operation.—Referring to Fig. 3: The end portion 16 of the necktie 14 is introduced, face out, between the normally positioned collar neckband 1 and flap 4 at collar point 4B, said necktie 14 being then drawn all the way around the neckband 1, Fig. 1, with emergence of said necktie end 16 at collar point 4A, said necktie end 16 being continued outwardly to a proper length stance with necktie end 15 for forming the knot 18. When said necktie 14 is so drawn around the neckband 1 to said stance, the necktie shoulder 17 (Fig. 2) and the adjacent rear

surface of the necktie 14 come into contact with the upwardly inclined said members contained on the neckband 1 (Fig. 1), starting said necktie 14 contact on the member 5 and continuing in contact with successive members 6, 7, 8, 9 and 10, the face portion of the necktie (opposite to shoulder 17 contained on the rear portion), also engaging the upwardly inclined flap member 11, thereby, by said engagement, elevating the necktie body 14 upwardly until the top necktie edge 14B rests in the crotch 12, desirably.

Presuming that the collar body lower edge 14A did rest at the bottom neckband edge 1A at a time that the collar and necktie bodies were in the relation shown in Fig. 3, nevertheless, when the knot 18 is drawn in and positioned against or adjacent the collar button 3 there would be sufficient moving necktie engagement with the said members 5 to 11 to elevate said necktie 14 snugly into the crotch 12, all around the collar inner surface, aforesaid. When said necktie comes to rest after said engagement, the said members 5 to 11 serve to position and hold said necktie against sagging or undue movement.

From the construction and operation of the invention as herein set forth, many general advantages will be seen and further implied.

It is further made known that the collar flap structure may contain a plurality of longitudinally spaced necktie engaging and reinforcing members if the flat laying stitches or fastening means appearing on the sight or outside surface of said flap are not considered objectionable over and above the one such flat laying stitch contained on the rear center of the flap, inconspicuously.

It will be recognized that when a collar is positioned normally on a wearer's neck portion, that the back of said collar is normally higher, by about 30 degrees, than is the front portion of said collar, thus, it is manifest that when the end portions of any necktie, contained normally by said collar, are drawn as high as possible in the front collar crotch portions, that the middle rear portion of said contained necktie can rise no higher than the level of the said necktie end portions contained at the top of said collar front crotch portions, there being, before my invention, no ready means provided for elevating a necktie so that the same would rest snugly all around in the crotch portion of said collar, or, that followed the crotch contour of said collar, or, that prevented the collar from being put in an awry stance due to the uneven constriction of the necktie on the collar neckband, thereby detracting from the dressy appearance desired in a collar and necktie relation.

It will be understood that the necktie elevating means are efficiently operable on any neck size or height of collar, or with any form of drawable necktie.

Inasmuch as the necktie is prone to engage

only the protuberant member high spots in the necktie's traverse around the neckband exterior and flap interior with an avoidance of contact with the greater base surfaces thereof, it is obvious that less necktie pull is required, as friction is minimized thereby and if said minimized friction function be considered of prime importance over the other possessed functions or qualities, modification within the spirit and scope of the invention would admit of general friction avoidance on said base surfaces with a necktie engaging protuberance of any given form or substance arising suitably in bead or lengthier form from said base surfaces, thereby giving expression and function to the ball-bearing principle in a new and unused form. Applicant sought, in the herein set forth embodiment, to have the friction minimizing protuberant element perform additional function in the reinforcement, elevating and setting of necktie as herein described, and, instead of the protuberant element being imposed on the finished or semi-finished collar, a fabric or material may be utilized in which the protuberant element may be woven or otherwise imposed in suitable friction minimizing form or design thereon for use on the necktie engaging surfaces of said collar.

The various advantages and objects of the invention may be accomplished by modification 30 of the particular embodiment specifically set forth herein, and it is intended that the appended claims shall include all equivalent arrangements justly coming within their call.

Having thus described my invention, what I 35 claim as new and desire to protect by Letters Patent is:

1. A collar having a neckband comprising inner and outer surfaces with top and bottom terminals thereto, an arranged upwardly slanting necktie elevating ridge on the outer surface 40 of said neckband.

2. A collar having a neckband with an attached outer flap, said flap having inner and outer surfaces with top and bottom terminals thereto, an arranged upwardly slanting necktie 45 elevating ridge on the inner surface of said flap.

3. A collar having a neckband and an attached outer flap with respective inner and outer surfaces and top and bottom terminals thereto, an arranged upwardly slanting necktie elevating ridge on the outer surface of said neckband, and an arranged upwardly slanting necktie elevating ridge on the inner surface of said flap.

4. A collar having a neckband with an attached outer flap, said neckband and flap having respective inner and outer surfaces with top and bottom terminals thereto, an arranged plurality of upwardly slanting necktie elevating ridges on the outer surface of said neckband, and an upwardly slanting ridge positioned on the middle portion of the inner surface of said flap.

JOSEPH P. WILSON.
